UNITED STATES PATENT OFFICE.

MORRIS WEINGARTEN, OF NEW YORK, N. Y.

DESIGN FOR A STORE FRONT.

Application filed September 27, 1921. Serial No. 503,623. Term of patent 7 years.

To all whom it may concern:

Be it known that I, MORRIS WEINGARTEN, a citizen of the United States, and resident of the city of New York, borough of Manhattan, in the county of New York and State of New York, have invented a new and original Design for a Store Front, of which the following is a specification, reference being had to the accompanying drawings, forming part threeof.

The figure is a front elevation of a store front, showing my new design.

I claim:

The ornamental design for a store front, as shown.

MORRIS WEINGARTEN.
